UNITED STATES PATENT OFFICE.

ANDREW E. AVERRETT, OF SCHENECTADY, NEW YORK, ASSIGNOR TO
GENERAL ELECTRIC COMPANY, A CORPORATION OF NEW YORK.

INDUCTION-MOTOR.

SPECIFICATION forming part of Letters Patent No. 732,153, dated June 30, 1903.

Application filed April 21, 1903. Serial No. 153,588. (No model.)

To all whom it may concern:

Be it known that I, ANDREW E. AVERRETT, a citizen of the United States, residing at Schenectady, in the county of Schenectady 5 and State of New York, have invented certain new and useful Improvements in Induction-Motors, of which the following is a specification.

My invention relates to induction-motors, 10 and has for its object the production of an induction-motor having efficient and economical starting means.

In starting induction-motors a tremendous rush of current due to the great slip causes 15 the secondary poles to overpower those of the primary member and gives the motor a low starting torque. In order to prevent this objectionable result, it is common practice to provide a resistance in circuit with the secondary winding which is gradually cut out 20 as the motor speeds up; but the employment of such starting means necessitates the use of switching connections and sliding contacts, which are more or less complicated and ob- 25 jectionable. I avoid these complications and objections and attain the desired starting torque by making a portion of the secondary winding of iron. In the "squirrel-cage" armature shown in the accompanying drawings 30 this member takes the form of iron end rings, which replace the usual copper end rings and electrically connect the longitudinal conductor-bars. By the use of these iron end rings I obtain the desired high resistance 35 in the secondary winding at starting and a gradual reduction of resistance as the motor speeds up, because of the large "skin" effect in iron when used as a conductor for alternating currents. This skin effect or tendency 40 of an alternating current to avoid the central portions of solid conductors and to flow or pass mostly through the superficial portions in the case of iron produces a very great increase of impedance over the normal resist- 45 ance—that is, a very great increase of opposition to the current flow. Tests made with a straight iron bar one inch in diameter and an alternating current with a frequency of forty have shown that the skin effect in said 50 bar increased the impedance to nearly ten times the normal resistance. The skin ef-

fect is also dependent upon the frequency of the current passing through the conductor and is greatest when the frequency is highest. From this it follows that the impedance of 55 the secondary winding of a motor constructed with iron constituting a portion of said winding, as described, is greatest when the motor is first started, because it is at such time that the frequency of the induced current in 60 said winding is the greatest, and it also follows that the impedance gradually decreases as the motor speeds up and approaches synchronism.

In the accompanying drawings, in which 65 like characters refer to like parts, I have illustrated an induction-armature of the squirrel-cage type constructed in accordance with my invention.

In the drawings, Figure 1 is an end view of 70 the armature with a portion of the end ring broken away. Fig. 2 is a sectional view on the line 2-2 of Fig. 1; and Fig. 3 is an enlarged sectional view, similar to Fig. 2, of a portion of the armature.

The armature consists, essentially, of a spider 10, keyed to the shaft 11 and supporting at its exterior a laminated structure 12, clamped between end rings 13 through the agency of bolts 14. The laminated structure 80 12 is composed of sheet-metal punchings provided with suitable apertures for the reception of longitudinal copper conductor-bars 15. These conductor-bars are bolted at their opposite ends to iron rings 16, which are engaged by small supporting-lugs 17 on the clamping-rings 13. The clamping-rings are provided with blades 18, which are adapted to create a current of air for cooling the armature when in operation.

The construction here described is identical with that in common use except that the longitudinal conductors 15 are secured to iron end rings 16 instead of to copper rings, as heretofore.

From the above it is apparent that the current induced in the bars 15 will necessarily flow through portions of the iron ring during the rotation of the armature.

In view of the explanation at the beginning 100 of this description it is thought that the operation will be clear.

What I claim as new, and desire to secure by Letters Patent of the United States, is—

1. In an induction - motor armature, the combination of a core composed of magnetic material, and a winding on said core, part of which is iron and part copper.

2. In an induction - motor armature, the combination of a core composed of magnetic material, copper conductors extending lengthwise of said core, and iron end members electrically connecting said conductors.

3. In an induction - motor armature, the combination of an iron core, longitudinal copper bars embedded in said core, and iron end rings mechanically and electrically connecting said bars. 15

In witness whereof I have hereunto set my hand this 20th day of April, 1903.

ANDREW E. AVERRETT.
